UNITED STATES PATENT OFFICE.

GEORGE BUERMANN, OF NEWARK, NEW JERSEY.

DESIGN FOR A CHEEK-PIECE FOR BITS.

47,023.

Specification for Design.

Patented Mar. 2, 1915.

Application filed November 19, 1914. Serial No. 873,055. Term of patent 14 years.

To all whom it may concern:

Be it known that I, GEORGE BUERMANN, a citizen of the United States, residing at Newark, county of Essex, and State of New Jersey, have invented a new, original, and ornamental Design for Cheek-Pieces for Bits, of which the following is a specification, reference being had to the accompanying drawing, forming part thereof.

Figure 1 is a side view of a cheek piece

for bits showing my new design, and Fig. 2 is an edge view of the same.

I claim:

The ornamental design for a cheek piece for bits, as shown.

GEORGE BUERMANN.

Witnesses:

GERTRUDE PFAENDLER,
M. A. JOHNSON.
